[57] CLAIM

The ornamental design for a target arena play structure, as shown and described.

DESCRIPTION

FIG. 1 is a top plan view of a target arena play structure in accordance with the present invention;

FIG. 2 is a front elevation view of the target arena play structure of FIG. 1, the left, right and rear elevation views being identical thereto;

FIG. 3 is a front elevational detail view of the target arena play structure of FIG. 1, the left, right and rear elevation views identical thereto;

FIG. 4 is a top plan view of the target arena play structure of FIG. 3; and,

FIG. 5 is bottom plan view of the target arena play structure of FIG. 3.

The broken line showing of play structure is for illustrative purposes only and forms no part of the claimed design.
